UNITED STATES PATENT OFFICE.

PASCAL P. CHILD, OF ST. LOUIS, MISSOURI.

DESIGN FOR RISER FOR WAGON-SEATS.

Specification forming part of Design No. 5,251, dated September 5, 1871.

To all whom it may concern:

Be it known that I, PASCAL P. CHILD, of the city and county of St. Louis and State of Missouri, have originated a certain new and useful Design for a Seat-Riser for Wagons, &c., of which the following is a correct description, reference being had to the accompanying drawing.

A is the bottom bar, having two recesses in its lower side, leaving three bearing-faces or legs, a, and a perforated boss, b, for the attaching-bolt or screw by which the riser is attached to the top of the wagon-box. The end bars C are made in an ogee curve, and their upper ends are connected by a horizontal bar, D, having three bracket-lugs, d d², for the attachment of the seat, shown in dotted lines. From the mid-length of the bar D extend ogee-formed braces E, connecting the seat-bar D to the end bars or standards C, as shown. This seat-riser differs from those before used chiefly in the introduc-

tion of the connecting-bar D, having a lug, d², at its mid-length, and the connecting-braces between the bar and the standards; also in the form of bearing-surface of the base-bar.

The riser, besides being more ornamental than those heretofore used, has the following points of superior utility: First, the bar D and lug d² give a firm rest and attachment to the seat-board, so that it cannot become warped. Second, the riser is so fully braced that a much stronger article can be made with the same amount of metal. Third, the riser has a more ornamental appearance.

I claim—

The design for the seat-riser for vehicles, substantially as above set forth.

PASCAL P. CHILD.
